INKED RIBBON SPOOL

John W. H. Bishop, Montreal, Quebec, Canada, assignor
to Bishop Spools, Inc., New York, N.Y., a corporation
of New York

Filed Oct. 2, 1962, Ser. No. 71,960

Term of patent 14 years

(Cl. D41—1)

FIG. 1

FIG. 2

FIG. 3

FIGURE 1 is a plan view of an inked ribbon spool, showing my new design as seen from above;

FIGURE 2 is a cabinet projection thereof as shown in FIGURE 1, said spool being rotated 90° clockwise and inverted; and

FIGURE 3 is an isometric view thereof as seen from above.

I claim:

The ornamental design for an inked ribbon spool, as shown.
